UNITED STATES PATENT OFFICE.

PATRICK J. HALLORAN, OF BOSTON, MASSACHUSETTS.

WINDSHIELD CLEANER.

Application filed May 8, 1928. Serial No. 276 045.

This invention relates to a windshield which includes a plurality of spaced apart wipers extending vertically across a windshield pane and reciprocated edgewise in contact with the pane by an oscillatory crank-arm, the wipers being adapted to collectively wipe a large area of the pane.

The chief object of the invention is to enable a windshield characterized as above stated to be reciprocated by an oscillating crank-arm with a minimum of frictional resistance, and a minimum expenditure of force.

Of the accompanying drawings forming a part of this specification,—

Figure 1 is a fragmentary perspective view, showing a windshield cleaner embodying the invention, the windshield and portions of the tracks and crank-arm hereinafter described being omitted, the cleaner including two wipers.

Figure 2 is a front elevation of a windshield and a cleaner embodying the invention associated therewith, the cleaner including three wipers.

Figure 3 is a fragmentary section on line 3—3 of Figure 2.

Figure 4 is a fragmentary section on line 4—4 of Figure 2.

Figure 5 is a fragmentary section on line 5—5 of Figure 2.

The same reference characters indicate the same parts in all of the figures.

In the drawings 12, 12 designate horizontally extending tracks in fixed relation to the frame 13 and pane 14 of a windshield, the tracks being preferably flat sided metal strips or bars, attached at their ends preferably to the frame 13, by fastenings 15, the tracks being offset from the outer side of the pane 14, as indicated by Figure 3.

16 designates a rock-shaft journaled in a bearing above the pane 14, the bearing being, in this instance, in the top member of the frame 13. The rock-shaft is provided with a crank-arm 17, which is spaced from the outer side of the pane 14, as shown by Figure 3, and is oscillated in a plane parallel with said pane by turning movements of the rock-shaft.

An element of the cleaner is an oblong grid which is reciprocated in a rectilinear path by the oscillation of the crank-arm and is provided with a plurality of wipers 18 of compressible material, such as rubber, bearing on the outer side of the pane 14.

The grid includes a channeled middle

cross-bar, wiper-carrying end cross-bars, each cross-bar being provided at its ends with runner portions slidably engaged with the tracks, and tie-rods 19, rigidly connecting the 60 cross-bars.

The channeled middle cross-bar includes two spaced apart side portions 20, which may be connected by a neck portion 21, and each end cross-bar is a single strip 22, the tie-rods 65 19 extending through the several cross-bars and being rigidly attached thereto. The wipers 18 may be attached to the cross-bars by any suitable means.

The runner portions of the cross-bars are 70 preferably provided by forming slots 23 in the ends of the cross-bars, the tracks 12 extending through the slots.

In the embodiment shown by Figures 2, 3, 4 and 5, the channeled middle cross-bar is 75 provided with a wiper 18, so that the grid has three wipers, while in the embodiment shown by Figure 1, only two wipers 18 are provided.

The tie-rods 19 maintain the channeled middle cross-bar midway between the end cross-bars. The inner faces of the side portions 20 of the channeled cross-bar constitute spaced apart abutments with which a terminal 25, on the crank-arm 17, is slidably engaged, said terminal being in this instance, an end portion of the crank-arm, bent at an angle to the major portion thereof, and bearing on said abutments, so that when the crank-arm is oscillated, its terminal 25 bears and slides first on one of said abutments, and then on the other, to reciprocate the grid on the tracks. The side portions 20 and the terminal 25 constitute a suitable embodiment of connecting means adapted to impart reciprocating movements from the crank-arm 95 to the grid.

In consequence of the location of the middle cross-bar midway between the end cross-bars, the location of the described connecting means is also midway between points where the end cross-bars contact with the tracks 12. The weight of the grid is supported mainly by the lower track 12, and the distance between the connecting means and each of the points 26, 26, where the end cross-bars bear on the lower track is practically the same, as indicated by lines 27, 27 in Figure 1. The weight of the grid is therefore so distributed that frictional resistance to movements of the grid on the tracks is reduced to a minimum, 110 the force required to oscillate the crank-arm and reciprocate the grid being considerably

less than would be required if the channeled cross-bar were at one end of the grid.

When the windshield is relatively wide and the crank-arm is relatively long, two wipers 5 18 are sufficient, each wiper being adapted to slightly overlap the track made by the other.

When the windshield is relatively narrow, and it is desired to wipe practically the entire length of the pane, three wipers are required. In Figure 2 the extreme positions 10 of the grid are indicated by full and broken lines, and the rock-shaft is located at the mid-length of the frame 13. The rock-shaft 12 may be rocked by any suitable means, which 15 may include a well known motor 28, operated by suction exerted by a motor-vehicle engine, and a manually operable handle 29.

The windshield frame may be either fixed, or hinged so that it may be variously inclined. 20

The tracks are preferably adapted to be flexed outwardly between their attached ends to permit the engagement of the cross-bar runners therewith, the tracks being resilient, 25 so that they are adapted to spring edgewise into the slots 23.

I claim:

1. A windshield cleaner comprising horizontally extending parallel upper and lower 30 tracks in fixed relation to a windshield frame, a rock-shaft journaled in a bearing above the windshield pane; a crank arm oscillatable by the rock-shaft; an oblong grid reciprocable in

a rectilinear path by oscillating movements of the crank arm, and provided with a plurality of wipers bearing on the windshield pane, said grid including a middle cross-bar, wiper-carrying end cross-bars, each cross-bar being provided at its ends with runner portions slidably engaged with the tracks, and tie-rods connecting the cross-bars and maintaining the middle cross-bar midway between the end cross-bars; and connecting means adapted to impart reciprocating movements from the crank-arm to the grid, said means including a terminal on the swinging end of the crank-arm, and abutments on the middle cross-bar with which said terminal is slidably engaged, said connecting means being located midway between the end cross-bars, so that the weight of the grid is distributed and frictional resistance to reciprocating movements of the grid on the tracks is reduced to a minimum. 35 40 45 50

2. A windshield cleaner as specified by 55 claim 1, the wipers including a middle wiper fixed to the middle cross-bar.

3. A windshield cleaner as specified by 60 claim 1, the ends of the cross-bars being provided with open slots through which the tracks extend, said tracks being flexible so that they may be sprung edgewise into the slots.

In testimony whereof I have affixed my signature.

PATRICK J. HALLORAN.
